UNITED STATES PATENT OFFICE.

CHARLES D. LANSING, OF ASHTABULA, OHIO, ASSIGNOR OF ONE-NINTH TO HARRY W. LUETHI, ONE-NINTH TO C. STUART MYGATT, AND ONE-NINTH TO FRED R. HOGUE, ALL OF ASHTABULA, OHIO, AND ONE-FIFTEENTH TO ORA T. FELL, OF YOUNGSTOWN, OHIO.

FLYING-MACHINE.

1,181,019.

Specification of Letters Patent.

Patented Apr. 25, 1916.

Application filed May 5, 1915. Serial No. 26,116.

To all whom it may concern:

Be it known that I, CHARLES D. LANSING, a citizen of the United States, residing at Ashtabula, in the county of Ashtabula and 5 State of Ohio, have invented new and useful Improvements in Flying-Machines, of which the following is a specification.

This invention relates to flying machines, and one of its objects is to provide a machine which is adapted for directly ascending and descending without gliding action, which may be caused to hover or remain stationary in the air over any given point on the earth or water below, and which may 10 be landed at any given speed.

A further object of the invention is to provide a flying machine of the helicopter type wherein the lifting and sustaining propellers are arranged to operate in such manner as to render the machine inherently self-balancing.

A further object of the invention is to provide a machine in which a driving propeller of the tractor type is employed, 25 which may be adjusted to steer the machine laterally in either direction, and also admits of stopping and backing the machine while suspended in the air.

The invention consists of the features of 30 construction, combination and arrangement of parts herein fully described and claimed, reference being had to the accompanying drawings in which:—

Figure 1 is a top plan view of a flying 35 machine embodying my invention. Fig. 2 is a side elevation of the same. Fig. 3 is a front elevation of the machine, Fig. 4 is a sectional plan view on the line 4—4 of Fig. 2.

The frame 1 of the machine may be of 40 any suitable form and construction, and provided with any desired type of launching and landing gear (not shown). This frame includes a head portion 2 provided with a 45 series of radiating arms 3 arranged in X-shaped formation and upon which are supported a series of propellers 4 arranged to rotate horizontally on vertical axes 5. These propellers are arranged in longitudinally and transversely aligned pairs on opposite sides of the longitudinal and transverse centers of the machine, the propellers at the 50 opposite sides being revolved in practice in opposite directions so that the tendency of

one set of propellers to cause skidding or 55 side-drifting from lateral thrust will be counteracted by the lateral thrust of the other set of propellers.

Supported upon the frame 1 is an aviator's seat 6, and also supported upon the frame 1 is a suitable motor 7, the shaft 8 of which is provided at one end with a beveled gear 9 meshing with a beveled gear 10 on the lower end of a vertical shaft 11 which extends above the head portion 2 of the frame 65 and carries drive pulleys or sprocket wheels 12 connected by belts or chains 13 with pulleys or sprocket wheels 14 on the axes of the propellers 4, whereby said propellers are driven.

It will be evident from the foregoing that the propellers are adapted when set in action to lift the machine bodily from the ground, to sustain it in the air, and to admit of the machine ascending at any desired speed and 75 also descending at any desired speed without the necessity of the machine in either case having a gliding action. The speed of these propellers 4 may be regulated by varying the speed of the engine or otherwise so 80 as to simply support the machine without further lifting impulse, so that the machine may be caused to hover or remain stationary in the air over any given point on the earth or water below.

It will be observed that as the propellers 4 are grouped about the frame at equal radial distances from the vertical center thereof, and are arranged in longitudinally and transversely aligned pairs, the opposite 90 propellers of the transversely aligned pairs working in opposite directions, the four propellers will tend to establish counteracting resistances to any movement of the machine out of a balanced position, whereby the propellers in action operate to render the machine inherently self-balancing.

The shaft 8 of the motor extends forwardly and at its forward end carries a beveled gear 15 meshing with a similar gear 16 100 on the lower end of a vertical shaft 17. This shaft 17 is journaled upon a forward extension 18 of the frame structure and supports at its upper end a horizontal friction wheel 19 which is disposed within the space 105 bounded by a yoke 20 swiveled or pivoted to swing horizontally upon the upper end of said shaft. Journaled in the arms of

this yoke is a shaft 21 carrying a propeller 22, which is thus mounted to rotate in a vertical plane and in practice is employed both as a driving and steering propeller.

5 Engaging the surface of the friction wheel or disk 19 is a vertically disposed friction wheel or disk 23 which is feathered to slide upon and rotate with the propeller shaft and is provided with a grooved collar or 10 hub 24 engaged by a forked member 25 connected by means of a rod 26 with a control lever 27, whereby the friction wheel or disk 23 may be shifted across the face of the disk 19 between the center and periphery of said 15 disk to vary the speed of the propeller within determined limits without varying the action of the motor.

Fixed to the yoke 20 are laterally extending arms 21' which are coupled by connections 22' with a drum 23' on a control shaft 24', whereby the propeller 22 may be swung laterally to steer the machine sidewise in either direction. This propeller 22 is placed at the center of the forward portion of the 25 machine on a line between and below the forward lifting and sustaining propellers, so that normally its action will not interfere with the balance or trim of the machine. It will be evident that by controlling the propeller 22 through the medium of the gearing and operating means just described the machine may be driven ahead at any desired speed within its speed range 30 while it is being sustained by the action of

the propellers 4, without disturbing or varying the speed of the engine, and that by shifting the friction disk 23 to a neutral position the action of the propeller may be stopped without stopping the motor, while by shifting said disk 23 to a point in advance of the center of the disk 19 the propeller 22 may be driven in an opposite direction to brake or back the machine. By swinging the yoke 20 laterally the propeller 22 furthermore serves, as stated, as a means 45 for steering the machine laterally in a ready and efficient manner.

I claim:—

A flying machine including a frame structure, sustaining means carried thereby, a 50 motor, a vertical shaft driven therefrom, a yoke swiveled upon said shaft, a horizontal friction disk carried by the shaft, a shaft journaled upon the yoke, a driving propeller carried by said shaft, a friction disk 55 feathered to slide upon and rotate with the propeller shaft and adjustable over the face of the first-named disk, means for adjusting said adjustable disk, and means for swinging the yoke laterally in either direc- 60 tion.

In testimony whereof I affix my signature in presence of two witnesses.

CHARLES D. LANSING.
